UNITED STATES PATENT OFFICE

2,560,816

VALVE GRINDING MACHINE

Simon J. Petersen, Miami, Fla., assignor to Imperial Products, Inc., Miami, Fla., a corporation of Florida

Application August 13, 1947, Serial No. 768,336

9 Claims. (Cl. 51—29)

1

In my application Serial Number 710,711, filed November 18, 1946, which issued at Patent No. 2,480,259, dated August 30, 1948, there is shown and described an improved machine or device of this character embodying a tool carrying shaft driven by a motor embodied in the tool, the shaft being given an oscillatory movement during the grinding operation, and which will automatically shift itself from one position to another during the grinding operation, so that the entire surface of the work being operated upon will be evenly ground.

In the aforesaid device, provision is made whereby the shifting thereof will be controlled by the pressure exerted upon the grinding tool, by reason of its contact with the surface being operated upon, or the resistance created by the work upon the tool or device, and the tool is operated from the motor through the medium of a gear device.

The present invention is an improvement upon the prior machine or device in that there is provided a clutch device in the driving mechanism, preferably of the spring type, to protect from damage the unit if the gear mechanism fails to function properly, or if the housing unit is set too tight.

A further object of the present invention is to provide an angle drive mechanism, to enable the user to operate with the tool upon valves that are in a position to which it has not heretofore been possible to gain access with the grinding tool in a vertical position, or which valve may be in a position that it is difficult to grind.

A further object is to provide an improved vacuum cup disc adapter thereby adapting the tool for use in grinding or reseating valves which have been burned or destroyed to the extent that a vacuum cup will not hold to the valve, the adapter being shaped to fit valves having various means, such as a number of driving holes, slots or cavities in the top of the valves.

A further object is to provide an improved tool or device of this character, which will be of a simple and compact construction, easy to handle, and effective and efficient in operation.

To the attainment of these ends and the accomplishment of other new and useful objects as will appear, the invention consists in the features of novelty in substantially the construction, combination and arrangement of the several parts, hereinafter more fully described and claimed, and shown in the accompanying drawings, in which:

2

Figure 1 is a view partly in side elevation, partly broken away, and partly in section, of a machine or tool of this character embodying this invention.

5 Figure 2 is an exploded view of some of the parts shown in Figure 1.

Figure 3 is a detail sectional view, on an enlarged scale, of the clutch mechanism.

10 Figure 4 is an enlarged detail sectional view on line 4—4, Figure 1.

Figure 5 is a plan view of support for the driving assembly.

15 Figure 6 is an exploded view of the parts shown in Figure 3.

Figure 7 is a detail sectional view of another form of clutch device.

Figure 8 is a sectional view of an angle drive vacuum cup adapter.

20 Figure 9 is a detail sectional view of a vacuum cup driving disc adapter.

Figures 10, 11 and 12 are views of the driving disc adapter.

25 Referring more particularly to the drawings, the device consists essentially of a casing or housing 15, in which is located a motor having a driving shaft 16, the motor being supplied with current from any suitable source, through the medium of a conductor 17, and is controlled in its operation by means of a suitable switch de-

30 vice 18. Within the motor casing 15, is a wall or partition 19, provided with a portion 20 forming a bearing through which the shaft 16 passes.

Seated in the housing and spaced from the wall thereof, preferably by means of an internal

35 flange 21, is a rotary drive ring gear 22, the teeth 22a of which are beveled and encompass the shaft 16. The gear is provided with a recess 22b, which receives a projection 22c, on the wall 19, for maintain the ring gear in position and for maintaining it against rotation with

40 respect to the casing.

A pinion gear 23, is secured to the shaft 16, preferably beyond the ring gear 22. Supported by the housing 15, is a support, preferably of

45 sectional construction and embodying two sections 24, 25, which latter may be connected together in any suitable manner such as by means

40 of a threaded joint 26.

The section 24, is provided with a wall 27,

50 in which is journaled a series of shafts, 28, 29

and 30, the shafts being journaled in suitable

extension bearings 31. To the shaft 28, is se-

55 cured a gear 32, which meshes with a pinion

gear 33, that is carried by a gear 34 on the shaft

59 29. To the shaft 30, is connected a pinion 35,

that is carried by a gear 36, and which pinion meshes with the gear 34.

The pinion 28, meshes with the gear 36, so that when the motor shaft 16 is rotated, the desired speed of rotation will be imparted to the shaft 28, through the medium of the intermediate gears.

Connected to the shaft 28 is a crank 37, having a projecting pin 38, which latter projects into a bifurcation or slot 39, in a crank arm 40, that is carried by a shaft 41. All of the gear mechanism thus far described is disposed within the section 24 of the support, and all of such gear mechanism, including the cranks 37 and 40, with the exception of the gear 23, that is carried by the motor shaft, are removable with the support as a unitary structure.

The bottom section 25 of the support is provided with an extension 42 forming a bearing for a shaft 41. Within the section 25, and through which section the shaft 41 projects, ball bearings 44, 45 are provided, which are spaced from each other and in which bearings this shaft is journaled.

The support embodying the sections 24, 25, is rotatably held in position with respect to the casing 15, in any suitable manner, and to that end the support telescopes into the lower end of the casing 15, so as to be disposed adjacent the flange 21, and a retaining collar 46 is threaded into the end of the casing and engages under a peripheral flange 47, on the section 24.

Disposed between the upper end of the section 24 and the flange 21 in the casing 15 is an annular member 48 having a peripheral flange 49 and which flange projects between the end of the collar 46 and the flange 21. This member 48 telescopes into the upper end of the section 24, and is maintained against rotation with respect thereto, in any suitable manner such as by means of an anchor pin 50.

Carried by the member 48 and disposed transverse to the axis of the member is a stub shaft 51, which is fixed with respect thereto. This shaft is of any desired length and sleeved thereon is a bevel gear member 52 preferably having a sleeve extension 53, and is rotatable on said shaft. Said gear has associated therewith a clutch friction plate 54. Rotatably mounted upon the sleeve 53 and disposed to cooperate with the friction plate 54, is a worm gear 55, which is also provided with a tubular extension 56, the side 57 of the gear being adapted to engage the plate to create friction therebetween. A retaining washer 58 is mounted upon the sleeve 56, and a spring pressure plate 59 is mounted upon the extension 53 of the gear 52. A spring 60 of any suitable construction is mounted upon the end of the sleeve 53, and operates to create friction with the plate 54.

The spring 60 is sealed in a recess 61 in the sleeve 53, and a cotter pin 62^a seated in an opening 54^a in the shaft 51 holds the parts assembled. The shaft 51 is so positioned that the gear 52 meshes with the ring gear 22, and the worm gear 55, meshes with a worm 62 carried by an extension 63, on the end of the shaft 28.

When the motor is operating, the shaft 16, will be rotated to rotate the gear 23, and this gear will rotate the gears 36, 35, 34, 33, and 32, thereby imparting rotary motion to the crank shaft 28. The rotation of the crank will impart an oscillating motion to the shaft 41.

The rotatable support 24-25 will be rotated at all times, whether idling or under load, due

to the direct gear connection with the motor through worm 62, worm gear 55, bevel gear 52 and ring gear 22, and will not depend upon resistance or pressure exerted upon the work.

In order to prevent damage from being done to the rotating assembly, the clutch mechanism is provided. The spring clutch is engaged at all times, and is driving the unit forwardly, and the tension or friction created therein, is such that it cannot slip backwardly.

The object of the clutch is that in case rotation is prevented in any way, damage is prevented, that is the power applied to the rotating gears will allow the clutch to slip, thus allowing the rotating unit to be stalled with no damage to the rotating assembly; the gear ratio is such that a great gear leverage is created.

In Figure 7, there is shown a modified form of clutch mechanism, wherein the worm gear 63, which corresponds with the gear 55, is provided with a slotted hub 64, to provide spring fingers which are depressed so as to frictionally bind the gear upon the sleeve or extension of the gear 52, and a sufficient friction will be created to make the clutch operate properly.

In order to adapt this tool or device for use in any type of car, wherein the motor is mounted back against the cowl, or so close to a wall or abutment, that it is not possible to grind the last valve with the grinding tool in a vertical position, there is provided an adapter which embodies two sections 65, 66 which are connected together by means of a universal joint or coupling 67^a. Carried by the free end of the section 65, is a disc 67 having a peripheral flange 68 which is engaged by a suction cup 69, carried by the tool shaft 41. To the free end of the section 66 is connected, in any suitable manner, a suction cup 79, that engages the valve 78, to rotate the latter upon its seat.

The section 66 is journaled in a housing 72, by means of ball bearings 73-74. A flange 75 which forms an integral part of the section 66 rests against one end of the housing, and an adjustable nut or collar 76 engages the other end of the housing 72.

In use, the motor casing or housing 15 is held in one hand while the adapter housing 72 is held in the other hand, during operation of the tool or device.

Thus it will be seen that the tool may be placed at any angle with respect to the motor casing 15 and can be operated at any angle.

In this form of the invention the valve 78, is shown as being in a condition that the suction cup 79 will sufficiently grip the same so that the valve can be rotated on its seat.

Many valves however, are slotted as at 80, and are burned to the extent that a suction cup will not hold to the valve. In such instances an adapter 81, is provided with a projection 82, adapted to be seated in the slot 80, thus connecting the adapter directly to the valve. The suction cup 69, is then applied to the adapter, and the valve can then be ground. In some instances the valves are provided with two holes drilled in the head for driving the valve. In this instance the adapter 83, is provided with two pins or projections 84, to project in said holes.

While the preferred forms of the invention have been herein shown and described, it is to be understood that various changes may be made in the details of construction and in the combination and arrangement of the several parts, with-

in the scope of the claims, without departing from the spirit of this invention.

What is claimed as new is:

1. A portable valve grinding device including a rotatably mounted support, a tool carrying shaft supported thereby for movement therewith and for oscillatory movement with respect thereto, a motor, an operative connection between the shaft and the motor for oscillating the shaft, means connected between the support and the shaft for imparting a rotary motion to said support while the shaft is oscillating, and friction clutch means associated with said last named means normally operable to drive rotatably said support, but adapted to slip under conditions of excess resistance to the operation of the shaft to stop rotation of said support and prevent injury to the oscillating means between the motor and shaft.

2. A portable valve grinding device including a rotatably mounted support, a tool carrying shaft supported thereby for movement therewith and for oscillatory movement with respect thereto, a motor, an operative connection between the shaft and the motor for oscillating the shaft, means connected between the support and the shaft for imparting a rotary motion to said support while the shaft is oscillating, and a friction clutch in the last said connection, said clutch being of a strength to maintain the support against retrograde movement.

3. A valve grinding device including a motor, a support rotatably mounted with respect to the motor, a tool carrying shaft mounted upon the support for bodily movement therewith and for movement with respect thereto, means operatively connecting said shaft with the motor for moving the shaft with respect to the support, a driving connection between the shaft and the support to cause the support to be rotated, and a frictional clutch device embodied in the last said connection normally operable to drive rotatably said support, but adapted to slip under conditions of excess resistance to the operation of the shaft to stop rotation of said support and prevent injury to said driving connection.

4. A valve grinding device including a motor, a support rotatably mounted with respect to the motor, a tool carrying shaft mounted upon the support for bodily movement therewith and for movement with respect thereto, means operatively connecting said shaft with the motor for moving the shaft with respect to the support, a driving connection between the shaft and the support to cause the support to be rotated, and a frictional clutch device embodied in the last said connection, the said clutch device embodying a gear and a worm gear, the axes of rotation of said gears being disposed transverse to the axis of the said shaft.

5. A valve grinding device including a motor, a support rotatably mounted with respect to the motor, a tool carrying shaft mounted upon the support for bodily movement therewith and for movement with respect thereto, means operatively connecting said shaft with the motor for moving the shaft with respect to the support, a driving connection between the shaft and the support to cause the support to be rotated, a frictional clutch device embodied in the last said connection, the said clutch device embodying a gear and a worm gear, the axes of rotation of said gears being disposed transverse to the axis of the said shaft, and a ring gear meshing with the first said gear for rotating it.

6. A valve grinding device including a motor, a rotatable support, a tool shaft bodily movable with and also movable with respect to the support, a drive connection between the motor and said shaft for actuating the shaft with respect to the support, said connection embodying a crank shaft, a drive connection between the crank shaft and the support for rotating the latter, the last said drive connection embodying a safety clutch device automatically releasable under excessive resistance to the operation of the tool shaft, said clutch embodying a driving gear and a worm gear connection between said driving gear and said crank shaft, and an annular stationary gear with which the said driving gear that is associated with the worm gear meshes.

7. A valve grinding device including a motor, a support rotatable with respect to the motor, a tool shaft journaled in the support bodily movable therewith and movable with respect thereto, a driving connection between the motor and tool shaft for operating the latter with respect to the said support, said connection embodying a crank shaft, a driving connection between the crank shaft and said rotatable support for rotating the latter, the last said driving connection embodying a worm gearing between the crank shaft and the rotatable support, and a spring biased friction clutch device for controlling the rotation of said support.

8. In a valve grinding device, a rotatably mounted support, a tool carrying shaft journaled therein, means for oscillating the shaft with respect to the support, means connected between the first named means and said support for rotating said support while the said shaft is being oscillated with respect to the support, and a clutch device associated with said last named means automatically operable under conditions of excess resistance to the operation of the shaft to stop rotation of said support and prevent injury to the oscillating means, the said clutch device embodying driving means and driven means carried by the rotatable support, said driving means having frictional driving engagement with said driven means under load conditions less than said conditions of excess resistance to the operation of the shaft.

9. A valve grinding device comprising a housing, a motor mounted in the housing and having a motor shaft extending through said housing, a pinion secured to said motor shaft, a ring gear fixedly mounted on said housing, a support rotatably mounted on said housing, a first shaft journaled in said support and having its axis out of alignment with the axis of the motor shaft, a gear secured to said first shaft, gearing drivingly connecting said pinion with said gear, a worm mounted on said first shaft, a second shaft carried by said support and arranged at right angles to said first shaft, a bevel gear rotatably mounted on the second shaft and meshing with said ring gear, said bevel gear having a sleeve extension on which is formed a clutch friction plate, a worm gear rotatably mounted on the sleeve extension of said bevel gear and meshing with said worm, a spring for urging a surface of said worm gear into frictional driving engagement with said clutch friction plate, whereby rotation of the motor shaft will cause said support to rotate with respect to said housing, a tool carrying shaft rotatably mounted in said support and arranged in axial alignment with the motor shaft, a crank arm at one end of said 70 tool carrying shaft and having a slot formed

therein, a crank secured to said first shaft and having at its outer end a pin which is received by the slot in said crank, and a valve engaging suction cup at the other end of said tool carrying shaft.

SIMON J. PETERSEN.
